(57) **CLAIM**

The ornamental design for a depilatory device, as shown and described.

DESCRIPTION

FIG. 1 is a front side perspective view of the present invention;

FIG. 2 is a front view of the present invention;

FIG. 3 is back view of the present invention;

FIG. 4 is a side view of the present invention;

FIG. 5 is another side view of the present invention;

FIG. 6 is a top view of the present invention; and,

FIG. 7 is a bottom view of the present invention.
